[57] CLAIM

The ornamental design for a desk top decoration or container for holding pencils or the like, substantially as shown and described.

DESCRIPTION

FIG. 1 is a top perspective view of a desk top container for holding pencils or the like showing my new design;
FIG. 2 is an elevational view, the opposite side being a mirror image thereof;

FIG. 3 is a bottom plan view thereof;

FIG. 4 is a top plan view thereof; and

FIG. 5 is a fragmentary view looking from the right of
